MOUNTING BRACKET

Floyd J. Balthaser, San Gabriel, Calif.

Application June 16, 1947, Serial No. 754,917

3 Claims. (Cl. 248—251)

1

This invention relates to a mounting bracket of the type adapted to be attached to a support in pairs so as to suspend between them jointly a towel bar or the like.

Conventional towel bar brackets require that a separate mounting plate be fastened to the wall as a preliminary step in mounting the bracket, and that the bracket itself be provided with a recessed base flange large enough to contain and conceal the mounting plate so that the bracket, when in operative position, presents a neat, finished appearance without revealing the screws by which the plate is secured. Moreover, it is customary practice to fasten the bracket to the plate by means, such as a set screw, which can be tightened to lock the bracket rigidly to the plate, or released to permit the bracket's removal from the plate. Such locking means must be small and customarily are located in such a position as to be as inconspicuous as possible, with the result that tightening and loosening thereof requires the use of a special tool, and even with such a tool is awkward and difficult and is most apt to result in damaging the surface of the wall upon which the installation is made. It is an object of my invention, therefore, to provide a mounting bracket of the character indicated which is of unitary construction to the extent that it is adapted to be mounted directly upon a wall or other suitable supporting structure, by driving screws or other suitable fastening means through holes provided for the purpose in the body of the bracket itself, thus avoiding the necessity of utilizing a separate mounting plate, and yet which is of such novel design that when the installation is complete, the screw heads are concealed from view and the bracket presents a pleasingly neat and finished appearance.

It is a further object in this connection to provide such a bracket having attachment openings for the insertion of screws or the like, which openings are accessible to a screwdriver disposed perpendicularly with respect to the supporting surface even though they are concealed from view in the mounted unit.

Another purpose is the provision of such a mounting bracket having a readily detachable, resilient retaining member which serves the double purpose of closing the opening in which the screw heads are accessible and holding the towel bar in place.

Other objects and advantages of the invention will be apparent from the following description and claims, the novelty consisting in the features of construction, combination of parts, the unique

2

relations of the members and the relative proportioning, disposition, and operation thereof, all as more completely outlined herein and particularly pointed out in the appended claims.

5 In the drawings, which form part of the present specification:

Figure 1 is a top plan view of a pair of my mounting brackets with a towel bar suspended between them.

10 Figure 2 is a front end elevational view of the same.

Figure 3 is a longitudinal sectional view taken through one of the brackets along the line 3—3 of Figure 2, with the direction of view as indicated.

15 Figure 4 is a view of the inner face of the bracket with the mounting spring in place, as viewed along the line 4—4 of Figure 3.

My improved mounting brackets 10 are adapted 20 to be secured to a wall or backing element 12 in pairs so as to suspend jointly between them a rod or bar 14, spaced outward from the wall and thus disposed in position to have a towel or the like hung over it. The two brackets of such a pair 25 are similarly formed but are faced in opposite directions in mounting, that is, opening toward each other so as to engage the bar between their open faces as will be more evident shortly.

Each bracket 10 is constructed of a flat base 20 plate 16 formed with a number of transverse openings 18 for insertion therethrough of screws 20 or the like so as to attach the bracket rigidly to the wall. From the outer side and end edges of the base there projects forward an extension arm 21 generally U-shaped in transverse section and constructed of an integrally formed side wall 22, top wall 24, and bottom wall 26. Hence, the arm 21 is hollow and is open along its inner side substantially throughout the length of the arm. Instead of extending straight out from the base plate, the arm is preferably curved, and is offset toward the side wall 22 so that an integral knob portion 28 on the outer end of the arm 21 is in approximate alignment with the outer end of the base plate 16. By this arrangement it will be apparent that the screws 20 are easily available for insertion or removal by a screwdriver extending straight out therefrom since they do not underlie any portion of the knob 28.

50 The inner face of the knob 28 has a laterally projecting lip 30 on its outer end formed around its three sides, the lip thus being in effect an extension of the side wall 22, top wall 24 and bottom wall 26, so they serve to define a generally 55 rectangular recess 32, open on two sides. The

towel bar 14 is adapted to seat in this recess with its flat end disposed in abutment against the corresponding inner surface of the knob.

Adjacent the inner edge of the base plate 16 there is provided a transverse, V-shaped groove or notch 34 cut in its top face. A resilient, detachable, retaining member 36 is adapted to have one end of an inwardly bowed section 38 inserted in such notch, the opposite end of the spring being bent approximately at right angles thereto to form a flat, rectangular tab 40 designed to abut against the back face of the end knob 28 and the inner face of the towel bar 14. When the tab is seated in this position, a little pressure on the bowed section 38 will cause its end to subsequently lodge in the notch 34, thus holding the towel bar 14 in place.

In order to remove the bar, the bowed portion of the spring is simply pressed in until its end disengages from the groove 34, whereupon the whole retaining member 36 can be slipped out of the bracket. The loosened end of the towel bar is then swung in toward the base plate 16 so that the opposite end of the bar can be withdrawn from the opposite bracket recess.

Thus it will be seen that I have combined a simple and rapid arrangement for mounting and demounting a towel bar, with a bracket construction which permits the bracket to be attached directly to the wall by screws through its base, which screws can be manipulated by a screw-driver projecting straight outward, the screws in addition being disposed out of sight in the completed assembly by reason of the retaining member. An additional advantage is obtained by reason of the fact that the brackets of a pair are identical and hence completely interchangeable so that dissimilar right and left hand brackets need not be provided.

While I have shown and described in some detail a presently preferred embodiment of my mounting bracket, it is to be understood that various modifications may be made in the construction and operation thereof within the spirit and scope of the subsequently claimed invention which is to be construed broadly and limited only by the prior art. It will be apparent, for example, that the shape of the recess 32 will be formed to correspond to the configuration of the towel bar inserted therein, and the latter, of course, need not be rectangular or square ended.

I claim:

1. A mounting bracket of the character described, comprising a base plate, an arm extending forwardly therefrom and comprising top and bottom walls and a side wall defining a U-shaped transverse section, a lip closing the outer end of said arm, said base plate having an attachment opening through a portion thereof surrounded on three sides by said walls of said arm and the outer portion of said arm being laterally offset to that side of said arm having said side wall where-

by said attachment opening is exposed to a tool inserted between said top and bottom walls of said arm and substantially perpendicular to said base plate, and a strip seated between said top and bottom walls of said arm and extending from said base plate substantially in flush relationship to the edges of said top and bottom walls to present a removable closure for the open side of said arm.

2. A mounting bracket of the character described, comprising a base plate, an arm extending forwardly therefrom and comprising top and bottom walls and a side wall defining a U-shaped transverse section, a lip closing the outer end of said arm, said base plate having an attachment opening through a portion thereof surrounded on three sides by said walls of said arm and the outer portion of said arm being laterally offset to that side of said arm having said side wall whereby said attachment opening is exposed to a tool inserted between said top and bottom walls of said arm and substantially perpendicular to said base plate, and means for releasably retaining a bar with its end seated against the inner face of said lip comprising a strip of resilient material extending longitudinally of said arm in position to present a closure for the open side thereof, said strip being flexed with one end pressing against said base plate and the other against said bar.

3. A mounting bracket for a towel bar, comprising a base plate, an arm extending forwardly therefrom, said arm comprising a web portion and parallel side flanges spaced apart to receive an end of a towel bar therebetween, said web and flanges cooperating to define a U-shaped section, an end flange substantially parallel to said base plate at the outer end of said arm and extending from said web between said side flanges, and a closure plate disposed in substantially flush relationship to the outer edges of said side flanges and being interposed between said base plate and said towel bar to retain said towel bar in position against the inner face of said end flange.
